UNITED STATES PATENT OFFICE

2,354,288

AUTOMATIC PEN FILLER AND CLEANER

Richard P. Aler, Baltimore, Md.

Application April 7, 1943, Serial No. 482,165

5 Claims. (Cl. 120—57)

This invention relates to new and useful improvements in devices for feeding ink to pens such as drafting pens and also means for cleaning pens of this type speedily and effortlessly.

The principal object of the present invention is to provide an apparatus which in response to a predetermined manual force subjected to a pen will deliver ink to the pen and which also includes a unit which by substantially the same action will clean a pen thoroughly, thus saving considerable time on the part of a draftsman.

Other important objects and advantages of the invention will become apparent to the reader of the following description.

In the drawings—

Figure 1 is a top plan view of the entire apparatus.

Figure 2 is a side elevational view of the apparatus looking toward the ink dispenser.

Figure 3 is a vertical sectional view showing the pen cleaner in side elevation.

Figure 4 is a fragmentary detailed sectional view taken substantially on the line 4—4 of Figure 1.

Figure 5 is an enlarged fragmentary detailed sectional view taken substantially on the line 5—5 of Figure 1.

Figure 6 is a fragmentary top plan view looking downwardly from the line 6—6 of Figure 2.

Figure 7 is a fragmentary elevational view looking at the cleaner element and the ratchet detent therefor.

Figure 8 is a fragmentary detailed sectional view taken substantially on the line 8—8 of Figure 1.

Figure 9 is a fragmentary top plan view showing one of the cradles.

Referring to the drawings wherein like numerals designate like parts, it can be seen that numeral 5 denotes a platform or base upon which two units A and B are mounted, the unit A being for the purpose of automatically feeding ink to pens, while the unit B is intended for the cleaning of pens by a substantially automatic operation.

The unit A embodies an upright 6 suitably secured as at 7 to the base 5 while a small tank 8 for containing ink is suitably secured as at 9 to its upper end. The tank 8 has a filler neck enclosure 10 and upon this tank is a riser 11 supporting a rockable beam 12 from one end of which extends a rod 13, this rod 13 extending through an opening 14 in the top of the tank 8 and downwardly into a tube 15 where the rod is provided with a piston 16 operative by the rod from one

side to the other of an opening 17 in the portion of the tube 15 within the tank 8. The tube 15 depends below the tank 8 and has a flexible hose or tube 18 extending therefrom to the upper end of an arcuate rigid pipe 19, this pipe, or tube extending longitudinally of the curved end portion 20 of a rocker 21, a dispensing nib 22 is provided at the lower end of the pipe 19.

The rocker 21 is fulcrumed as suggested in Figures 2 and 6, the rocker having a threaded opening therein through which a screw shaft 22 is disposed, this screw shaft being provided with a knurled head 23 at one end. The screw shaft is threadedly disposed through the upper portion 15 of a post 24 and journaled through an opposed post 25 where the screw shaft has a stop enlargement 26. Obviously, the purpose of the screw shaft 22 is to shift the rocker 21 horizontally so that the dispensing nib 22 can be properly located with respect to the position of the pen.

The rear end of the rocker 21 has a depending portion 27 and a horizontal tail portion 28 carrying a counter-balancing weight 29.

On a short post 30 rising from the base 5 is a short rocker 31, having one end connected by a link bar 32 to the tail portion 28 of the rocker 21. A link 33 connects the other end of the short rocker 31 to an ear 34 on the rear end of a cradle 35 which is intended to receive the ink receiving end of a pen 36. As is shown in Figure 9, one side wall *a* of the cradle is straight, while the opposed wall *b* curved, this for the purpose of conforming with the sides of the drafting pen 36.

The cradle 35 has a bearing structure 37 at its 35 intermediate lower portion through which a shaft 38 is disposed, this shaft being supported by a post 39 rising from the base 5.

A hood 40 is disposed over the cradle 35 and is supported by a rest 41. The hood is open for a portion of its top and at its forward side to accommodate both the ink dispensing nib 22 and a pen 36.

It can now be seen, that by first placing the pen on the cradle 35 and having the same snugly fit therein, the pen can be pushed down to rock the cradle and this, in turn, rocks the small rocker 31, imparting motion by way of the link 32 to the large rocker 21 and this, in turn, through the medium of a link 44 lifts the piston 16 in the valvular control shown in Figure 4 to release ink from the small tank or reservoir 8 to the pipe 19 and nib 22, as the nib lowers and engages the pen due to the incident rocking of the rocker 21. Should the nib 22 not properly contact the pen,

the shaft 22 (see Figure 6) can be adjusted to properly place the nib.

The cleaner mechanism denoted by the reference character B is in most respects identical in construction with the mechanism A, the unit B comprising briefly, a cleaning fluid reservoir 8a supported by a post 6a, a rocker 21a supported by posts 24a and having adjusting means 22a, a pipe 19a on a curved portion of the rocker 21a and this connected by a flexible hose 18a to a suitable valve in the tank 8a, which is controlled by a rocker 12a and a link 44a extending from the rocker 12a to the rocker 21a. The rocker 21a is counterbalanced by a weight 29a and the rocker 21a is operated by a cradle 35a which is connected by a link 33a to a small rocker 31a and this, in turn, is connected by way of a link 32a to the rear portion of the rocker 21a. In front of the cradle 35a is a rest 41a and above the cradle 35a and carried by the rocker 21a is a rotary cleaning element 50 mounted for rotation within a bifurcated portion 51 of the pipe 19a. The rotary cleaning element 50 is on a shaft 52 with a ratchet wheel 53 which is engaged by a tooth 54 on a spring arm 55 supported by a post 56. (See Figure 7.)

It can now be seen, that by pushing downwardly on the cradle 35a with a pen, the rocker 31a will be rocked and, in turn, the rocker 21a will be rocked to lower the cleaning element 50 and this results in the releasing of some of the fluid from the reservoir 8a to the pipe 19a and also because of the engagement of the tooth 54 against the ratchet wheel 53, the ratchet wheel will be caused to rotate and the cleaning element 50 likewise, so that when the cleaning element reaches the pen it is rotating and performs a cleaning operation on the pen. An up and down movement of the pen will cause continual rotation of the element 50 and a sufficient delivery of 40

cleaning fluid.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A pen inking unit including valve controlled feed means, a feed nib connected to the feed means, a rocker supporting the nib, cradle actuating means for the rocker and operable through

the medium of a pen when the latter is moved into engagement with the cradle and predetermined manual force applied to the pen, and counter-balancing means for the rocker.

5 2. A liquid feeding mechanism for a pen and comprising a reservoir having a valve, a rocker having a feed line connected to the discharge end of the valve, a cradle shaped to conformably receive a pen and connected to the rocker when the latter is moved into engagement with the cradle and predetermined manual force applied to the pen, means connecting the rocker to the valve, and means for adjusting the feed line relative to the cradle.

10 3. A liquid dispensing device for a tool of the class described and comprising a reservoir having a valve, a feed line connected thereto, a pivoted support to which the feed line is attached for movement with the support, means operatively connecting the valve to the support, a tiltable tool actuated cradle, and means operatively connecting the cradle to the pivoted support for simultaneously opening the valve and moving the discharge end of the feed line toward the tool when the latter is moved into engagement with the cradle and predetermined manual force applied to the tool.

15 4. A pen inking unit including a reservoir having a valve, a feed line connected thereto, a tiltable pen-engageable cradle shaped to conform with the ink holding end of a pen, a pivotal support for the feed line, and means operatively connecting the cradle with the valve and with the feed line support for simultaneously opening the valve and moving the feed line toward the pen when the latter is manually moved into engagement with the cradle and predetermined manual force applied to the pen for operation of the cradle through the medium of the pen.

20 5. A pen cleaning unit comprising a cleaning fluid reservoir, valve means for the reservoir, a feed line for the valve means, a rotary cleaning element at the end of the feed line, said cleaning element being provided with a ratchet wheel, 45 a rocker supporting the feed line and operatively connected to the valve means, means connected to the rocker and manually operable through means and actuating the rocker, and a stationary pawl in the path of bodily movement of the ratchet wheel and engageable therewith to actuate the ratchet wheel.

RICHARD P. ALER.
